FIG. 1 is a front, left and bottom perspective view of a combined solar power bank and solar panel showing the new design;

FIG. 2 is a rear, right and top perspective view of the solar power bank shown separated for ease of illustration;

FIG. 3 is a front, left, and bottom perspective view thereof;

FIG. 4 is a rear elevation view thereof;

FIG. 5 is a front elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a rear, right, and top perspective view of the solar panel shown separated for ease of illustration;

FIG. 11 is a front, left, and bottom perspective view thereof;

FIG. 12 is a rear elevation view thereof;

FIG. 13 is a front elevation view thereof;

FIG. 14 is a right elevation view thereof;

FIG. 15 is a left elevation view thereof;

FIG. 16 is a top plan view thereof;

FIG. 17 is a bottom plan view thereof; and,

FIG. 18 is an enlarged view of detail 18 in FIG. 10.

The dot-dash broken lines in FIGS. 10 and 18 depict the boundaries of the enlarged views and form no part of the claimed design.

1 Claim, 18 Drawing Sheets
